5 Claims. (Cl. 250—8)

(Granted under the act of March 3, 1883, as
amended April 30, 1928; 370 O. G. 757)

1

The invention described herein may be manufactured and used by or for the Government for governmental purposes, without the payment to us of any royalty thereon.

This invention relates to radio communication, and more particularly to improvements in radio telegraph systems employing means for automatically transmitting signals and automatically recording signals in print at a receiving station.

Radio signals as generally received are too feeble to actuate a relay, unassisted, for the purpose of controlling a telegraph printing device of the class known as Teletype. This inadequacy of the radio signal for the desired purpose is also aggravated by the radio phenomena known as fading and climatic conditions, which may, if occurring during the signalling period, cause loss of an impulse and the mutilation of the transmission code.

It is, therefore, an object of this invention to provide a novel electrical circuit and arrangement of elements whereby a received radio signal is sufficiently amplified to actuate a relay controlling a telegraph printing device.

A further object of the invention is the provision of a radio telegraph system in which the operation of a recording printer at a receiving station automatically causes a radio transmitter, which is already in operation at the receiving station, to retransmit the signal to the original transmitting station where the signal is received and a printed record made thereof, thus insuring the receipt of the message by the original receiving station.

These and other objects are attained by the novel circuit and arrangement hereinafter described and illustrated in the accompanying drawings, forming a part hereof, and in which:

Figure 1 is a schematic diagram of an electrical circuit embodied in the invention.

Figure 2 is a diagram of communication system according to the invention.

Referring to the diagram, a diversity radio reception system is shown to include three radio receiving sets 1, 2, 3, adapted to receive interrupted continuous wave signals. The antennas of the receiving sets are spaced by ten wave lengths from each other. The audio output of each receiver is separately rectified by rectifying

2

tubes 4, 5, 6, respectively, producing a combined negatively directed voltage which is passed through a filter to allow only the modulated frequency of the tone transmitted to pass.

5 The voltage from the filter is applied to the grid 8 of a direct current amplifying tube 7, the cathode 9 of which is returned to ground through the plate circuit 11 of a vacuum tube 10 of the beam power type.

10 The output of tube 7 is applied directly to the grid 13 of another vacuum tube 14, preferably of the beam power type. Normally with no signal input to the receivers, no negative voltage is applied to the grid of the direct current amplifier

15 7. This allows current to flow in the amplifier tube 7. This current flow places a high bias on tube 14, keeping the current in the plate circuit of tube 14 extremely low.

When the incoming signal has the proper 20 modulation frequency, negative bias is placed on the grid 8 of tube 7, causing the tube to draw less current, which lowers the bias voltage on the grid of tube 14, causing current to flow through the plate circuit of tube 14.

25 The plate current change in the direct current amplifier tube 7 is maintained at a very low value up to a predetermined value of negative grid voltage by the vacuum tube 10, which has its plate 11 connected to the cathode 9 of tube 7.

30 The voltage of tube 10 is stabilized by the assistance of a glow type voltage regulator tube 16. A negative grid voltage slightly above the predetermined negative grid voltage mentioned above causes a large change in the plate current of tube 7, thereby resulting in a great change in the bias of the tube 14. This being a positive change causes tube 14 to draw a large current. A sensitive relay is placed in the plate circuit of tube 14.

35 In operation the gain of the receivers is adjusted so that the voltage produced by the noise level is below the critical point of the grid of tube 7. If the incoming modulated continuous wave is above the noise level it will cause the voltage on the grid of the amplifier tube 7 to rise above the critical point.

40 In practice, a Teletype transmitter and receiver is used at each station. Two transmitting frequencies are used, one for transmitting an original message, and the other for retransmitting a received message back to the original transmit-

ting station. The incoming signal is received by one or more of the radio receivers, from which it is rectified, filtered and passed to the amplifier tube 7, to produce a current in the plate circuit thereof. A small current in tube 7 will cause a low bias of tube 14, and consequently cause the flow of a large current in the plate circuit of tube 14. This large current is of sufficient strength to actuate relay 50 which controls a Teletype apparatus 17 for receiving and printing a message. When one station is receiving its radio transmitter is placed on the air by closing contacts 19, to send out tone modulated signals. The transmitter is then keyed by the Teletype contacts in accordance with the standard Teletype five unit permutation code to cause the received message to be retransmitted by the transmitter 18 back to the original transmitting station where it is received and a printed record made thereof by the Teletype apparatus at the original transmitting station.

Thus, when message is transmitted by a first station to a second station, it is received by the second station and retransmitted back to the first station, where it is received and a printed record made thereof. The first station then knows definitely that the message has been received by the second station.

Should at any time the receiving station desire to interrupt the transmitting station, the radio transmitting keying circuit is opened by a manual switch, causing the Teletype machines at both stations to run open.

To insure minimum of static interference, either the transmitting or receiving antennas, or both, are of the V-beam type.

The invention having been described, what is claimed is:

1. In a control system, a source of direct current electromotive force; an actuating circuit; a triode including an anode, a cathode and a control grid; means connecting said grid and cathode to said actuating circuit and said anode and cathode across said source to place positive potential at said anode; said means including means responsive to the current fed to said cathode to greatly reduce said current upon a predetermined drop thereof and to greatly increase the same upon a predetermined rise thereof from its said reduced magnitude; a tube having a cathode, a control grid and an anode; wires connecting the last-named grid to the negative pole of said source and the last-named cathode to the first-named cathode; a circuit passing through said last-recited anode and cathode, said circuit including a source of direct current electromotive force therein; and means to be energized and deenergized in said last-named circuit.

2. A control system defined in claim 1 in which said first-named means comprises a tube having an anode connected to the cathode of said triode, a screen grid, and a cathode connected to said actuating circuit as well as to the negative pole of the first-named source of said claim 1; and means for supplying a constant high voltage positive potential at said screen grid with respect to the last-mentioned cathode whereby the plate current change in the first-named tube of claim 1 is maintained at a very low value up to a predetermined value of negative grid voltage and a change beyond said predetermined value effects prompt great change in the current.

3. In a control system; a triode having an anode, a control grid and a cathode; a second tube having an anode connected to said cathode, a screen grid subject to high constant positive potential, and a cathode; an actuating circuit connected to the first-named grid and the last-named cathode; a source of direct current potential having its positive pole connected to the first-named anode and negative pole connected to the last-named cathode; and a driven tube having an anode, a cathode and a grid; means connecting said negative pole to said grid of said driven tube; means connecting the cathode of said driven tube to the cathode of said second tube; and a circuit including the anode and cathode of said driven tube, a source of power, and means to be energized.

4. In a control system the combination with a circuit including therein means to be controlled of an actuating circuit; a triode including an anode, a cathode and a control grid; said grid and cathode being connected across said actuating circuit; a single tube for controlling pulses to the first-named circuit, including an anode and a cathode connected in said first-named circuit, and a control grid; a second circuit including the series current path of the first-named anode, the first-named cathode, the second-named cathode and the last-named grid, said series current path including a source of polarized electricity therein connected to affect the last-named grid negatively; whereby the last-named tube will be increased and decreased in conductivity inversely as the said triode; said first-named circuit including therein a source of power affecting the second-named anode positively; and means for increasing the degree of sharpness of said triode in becoming conducting and non-conducting in response to changes in the potential across said actuating circuit, the last-named means comprising means in the cathode circuit of said triode that saturates when the triode is not biased by said actuating circuit.
5. In a control system, the combination with a circuit including therein means to be controlled of an actuating circuit; a triode including an anode, a cathode and a control grid; said grid and cathode being connected across said actuating circuit; a single tube for controlling pulses to the first-named circuit, including an anode and a cathode connected in said first-named circuit, and a control grid; a second circuit including the series current path of the first-named anode, the first-named cathode, the second-named cathode and the last-named grid, said series current path including a source of polarized electricity therein connected to affect the last-named grid negatively; whereby the last-named tube will be increased and decreased in conductivity inversely as the said triode; said first-named circuit including therein a source of power affecting the second-named anode positively; and means for increasing the degree of sharpness of said triode in becoming conducting and non-conducting in response to changes in the potential across said actuating circuit, the last-named means comprising a tube having an anode connected to the cathode of said triode and a cathode connected to the said actuating circuit, said last-named tube including means whereby it is saturated by the current of said triode when the latter is not actuated by said actuating circuit.
